UNITED STATES PATENT OFFICE.

WILLIAM M. MERVIN, OF DETROIT, MICHIGAN.

DESIGN FOR A HEATER.

Application filed December 12, 1921. Serial No. 521,955. Term of patent 14 years.

To all whom it may concern:

Be it known that I, WILLIAM M. MERVIN, a citizen of the United States, residing at Detroit, in the county of Wayne and State of Michigan, have invented a new, original, and ornamental Design for Heaters, of which the following is a specification, reference being had to the accompanying drawing, forming part thereof.

In the drawing, Fig. 1 is a perspective view of a heater showing my improved design. Fig. 2 is a plan of the top of the heater.

I claim:

The ornamental design for a heater, as shown.

WILLIAM M. MERVIN.
